UNITED STATES PATENT OFFICE.

HALFDAN A. STEEN, OF MILWAUKEE, WISCONSIN, ASSIGNOR, BY MESNE ASSIGNMENTS,
TO ALLIS-CHALMERS MANUFACTURING COMPANY, A CORPORATION OF DELAWARE.

TIME-LIMIT CIRCUIT-BREAKER.

1,140,007.

Specification of Letters Patent.

Patented May 18, 1915.

Application filed April 8, 1911. Serial No. 619,692.

To all whom it may concern:

Be it known that I, HALFDAN A. STEEN, a subject of the King of Norway, residing at Milwaukee, in the county of Milwaukee and

5 State of Wisconsin, have invented certain new and useful Improvements in Time-Limit Circuit-Breakers, of which the following is a full, clear, and exact specification.

This invention relates to time element devices for electric switches.

In controlling electric apparatus it is very often desired that the time of a required operation shall be delayed for an appreciable interval after a change of condition occurs.

15 For example, when a circuit is overtaxed with current it would occasion considerable annoyance if the circuit were always immediately open, for the reason that the apparatus is not endangered by a brief interval

20 of overload. Also when there is an accidental ground it is undesirable to open the circuit unless the ground be of an enduring character. For these reasons there is often employed a time element device for retarding the operation of electric switches under abnormal circuit conditions which may be momentary or of an enduring character, in which latter case the endangered circuit will be opened within a safe limit.

25 The object of my invention is to provide an improved time element device for the purposes above set forth.

The various novel features of this invention will be described in the specification 35 and particularly set forth in the appended claims.

The invention is illustrated on the accompanying sheet of drawings, in which—

Figure 1 is a partial diagrammatic view 40 showing a generator circuit provided with a circuit-breaker in combination with my improved time element device. Fig. 2 is a front elevation of a modification of the above time element device shown submerged in a 45 liquid; and, Fig. 3 is a front elevation of the device shown in Fig. 2, the device being partially above the surface of the liquid.

A generator 10, here shown as having a shunt field 11, and mains 10^a and 10^b is provided with a line switch 12 and an automatically operated circuit-breaker 13. The circuit-breaker includes an arm 14 and link 15 between which is mounted a normally energized spring 16 adapted to open the 55 circuit-breaker upon certain predetermined

circuit conditions. The arm 14 is pivoted to a lug 17 of a liquid containing tank 18, and is held in circuit-closing position by having its upper end 19 engage a notched portion 20 of a trigger 21. This pivotally mounted trigger 21 is adapted to be raised out of engagement with the upper portion 19 of arm 14 by a rod 22 connected to a movable core 23. The core 23 is adapted to be actuated upon the occurrence of certain predetermined abnormal circuit conditions by a solenoid 24 which is included in the generator circuit. Fixed to the rod 22 is a cap-shaped suction member 25 having a leak valve 26 and another valve 27. Located 60 within the tank 18 is a quantity of liquid 28, preferably oil, in which the core 23, coil 24, and suction member are submerged. The suction member, under certain conditions, is actuated in and raised out of the liquid 65 28. For example, if an overload on the generator circuit arises, the solenoid 24 will be sufficiently energized to raise the core 23 and suction member 25. Due to the friction of the oil the upward movement of the suction member will be somewhat retarded. This retarded movement will continue even after the upper portion of the suction member is raised above the level 29 of the liquid 70 28. For example, if an overload on the generator circuit arises, the solenoid 24 will be sufficiently energized to raise the core 23 and suction member 25. Due to the friction of the oil the upward movement of the suction member will be somewhat retarded. This retarded movement will continue even after the upper portion of the suction member is raised above the level 29 of the liquid 75 28. For example, if an overload on the generator circuit arises, the solenoid 24 will be sufficiently energized to raise the core 23 and suction member 25. Due to the friction of the oil the upward movement of the suction member will be somewhat retarded. This retarded movement will continue even after the upper portion of the suction member is raised above the level 29 of the liquid 80 28. For example, if an overload on the generator circuit arises, the solenoid 24 will be sufficiently energized to raise the core 23 and suction member 25. Due to the friction of the oil the upward movement of the suction member will be somewhat retarded. This retarded movement will continue even after the upper portion of the suction member is raised above the level 29 of the liquid 85 28. For example, if an overload on the generator circuit arises, the solenoid 24 will be sufficiently energized to raise the core 23 and suction member 25. Due to the friction of the oil the upward movement of the suction member will be somewhat retarded. This retarded movement will continue even after the upper portion of the suction member is raised above the level 29 of the liquid 90 28. For example, if an overload on the generator circuit arises, the solenoid 24 will be sufficiently energized to raise the core 23 and suction member 25. Due to the friction of the oil the upward movement of the suction member will be somewhat retarded. This retarded movement will continue even after the upper portion of the suction member is raised above the level 29 of the liquid 95 28. For example, if an overload on the generator circuit arises, the solenoid 24 will be sufficiently energized to raise the core 23 and suction member 100 25. Due to the friction of the oil the upward movement of the suction member will be somewhat retarded. This retarded movement will continue even after the upper portion of the suction member is raised above the level 29 of the liquid 105 28. For example, if an overload on the generator circuit arises, the solenoid 24 will be sufficiently energized to raise the core 23 and suction member 110 25. Due to the friction of the oil the upward movement of the suction member will be somewhat retarded. This retarded movement will continue even after the upper portion of the suction member is raised above the level 29 of the liquid 28.

- temporary overload will not be sufficient to operate the circuit-breaker, but if the overload continues a certain predetermined time the circuit-breaker will be operated. When 5 the overload on the generator circuit discontinues, the rod 22 is permitted to return to its normal position much quicker than it was raised for the reason that the valve 27 will be opened providing for the passage of 10 a comparatively large volume of liquid in a short time. The rod 22, which is guided in the cap 30 of the tank 18, is held in its normal position by a collar 31 which engages the cap 30.
- 15 In Figs. 2 and 3 a modification of the time element or suction device illustrated in Fig. 1 is shown. Here, instead of using a shallow cap-shaped suction member, a deep cap-shaped suction member 32 is provided 20 which also has a leak valve 33 and valve 34 for a quick return movement. This suction member 32 is provided with diametrically opposite slots 35 and also with an adjustable collar 36 which is adapted to be moved 25 lengthwise of the shell 32 for varying the effective duration of the time limit. The suction member 32 acts precisely the same as member 25 with the exception that it provides for a longer or greater retarding 30 effect and is also provided with adjustable means for varying the length of the retarded effect. When the suction member 32 is raised partially out of the liquid the retardation of the upward movement continues 35 until the cap has raised to such an extent, as shown in Fig. 3, that the slots 35 have reached the level of the liquid in the tank 18, whereupon the rod shoots upward rapidly to trip the circuit-breaker.
- 40 This time element device is not only applicable for use as here illustrated, but can be applied wherever the use of a retardation or time element device is desirable.

There may be many modifications in the

precise form and arrangement here shown 45 and described, and I aim to cover all such modifications which do not depart from the spirit and scope of my invention, as set forth in the appended claims.

What I claim as new is:

1. A time element device comprising a receptacle containing a liquid, a movable member disposed outside of said casing, an electromagnet in said casing, the core of said magnet having a projection extending 55 through said casing and movable into engagement with said movable member to actuate the same, and a suction member normally immersed in said liquid and movable by said core out of said liquid, said 60 suction member being provided with a leak opening permitting the equalization of pressures within and without the suction member.

2. In combination, a receptacle partly 65 filled with liquid, a cover for said receptacle, a movable member disposed outside said receptacle, an electromagnet having a coil and a core therefor mounted in said receptacle, a suction member normally immersed in said 70 liquid and movable with said core, said suction member comprising a hollow element closed at its upper end and provided with a restricted opening between its upper and under sides and with means for varying the 75 depth of the imperforate portion of said hollow element below said restricted opening, and an extension from said core passing through said cover and engageable with said movable member to actuate the same. 80

Milwaukee, Wis., April 3, 1911.

In testimony whereof I affix my signature, in the presence of two witnesses.

HALFDAN A. STEEN.
